UNITED STATES PATENT OFFICE.

ALBERT O. MILLER, OF PORTER, MINNESOTA.

ALARM FOR ELEVATOR GRAIN BINS.

Application filed October 6, 1920. Serial No. 415,193.

To all whom it may concern:

Be it known that I, ALBERT O. MILLER, a citizen of the United States, residing at Porter, in the county of Yellow Medicine 5 and State of Minnesota, have invented certain new and useful Improvements in Alarms for Elevator Grain Bins; and I do hereby declare the following to be a full, clear, and exact description of the invention, 10 such as will enable others skilled in the art to which it appertains to make and use the same.

This invention relates to alarms for elevator grain bins. In filling the bins of 15 elevators, it is important and desirable to have some means of indicating when the grain has sufficiently accumulated therein, and thus prevent the overflowing and wasting of grain, and also preventing the grain 20 from entering compartments not designed for such purpose.

It is an object of this invention to provide a grain alarm consisting of few and simple parts, and one of efficient operation. It is 25 a further object of the invention to provide an alarm of such construction that it can be easily and quickly adjusted by an unskilled workman. These, and other objects of the invention, will be apparent as the description 30 proceeds, in connection with the accompanying drawings, in which like reference characters refer to the same parts throughout the different views, and in which,

Fig. 1 is a sectional elevation of an elevator showing the bins therein and applicant's novel alarm applied thereto; and

Fig. 2 is a perspective view of applicant's alarm device.

Fig. 1 shows a section of an ordinary grain 40 elevator comprising a wall 1, top 2, and the usual superstructure 3, which carries the conveying machinery. Within the elevator are shown bins 4 which are filled through openings 5 and which have the usual discharge devices 6 at their lower ends. Applied to one of the bins shown in Fig. 1, 45 is applicant's novel alarm device. It will, of course, be understood that one of these devices will be provided for each bin and as 50 many bins may be used as desired.

The alarm device proper consists of a supporting member 7 designed to be located in an opening 8 in the wall of a bin. This supporting member is shown as carried by 55 a bracket or lug 9 on the interior wall of

the bin. One end of supporting member 7 projects outside of the bin and has a slot formed therein. Superposed upon the member 7 is another slotted member 10 having therein a slot 12. An upright bracket 13 60 is rigidly secured to one side of the member 12 and carries a bearing pin 14, upon which is journaled for rotation, a sheave 15. This sheave is so disposed that a cord or rope passing thereover can pass vertically downward through the slot 12 outside of the bin. Secured upon and at one end of member 10, and extending into the bin is a slotted bracket 16 having a slot 17 therein. Bearing pin 18 is secured in the member 16 and 70 passes through said slot to form a pivot for an arm 19 which supports a bin board or grain board 20. The arm 19 and bin board 20 project downwardly into the bin, and a rope or flexible member 21 is secured to the underside of arm 19 as at 22 and passes from the same, over sheave 15 and down along the outside wall of bin 4. If necessary, this rope may be led over one or more guiding sheaves 23, as shown in Fig. 1. At its lower 75 end, adjacent the underside of the bin, this rope passes through a vertical hole in a bell crank arm 24, and below said arm is provided with an enlarged portion, such as a knot, shown as 25 in Fig. 1, or a block or 80 knob, such as shown at 26 in Fig. 2. Supported upon the bin structure, or other suitable means, is a bracket 27, to which is secured a pivot pin 28. The bell crank 24 85 is mounted upon the pivot pin 28 and adapted to oscillate thereon in a substantially vertical plane. The bell crank 24 comprises a substantially horizontal arm 29 and a shorter arm 30. The flexible member 21 passes through the arm 29, and at the end 90 of the arm, an extension 30 is formed, upon which is slidably mounted a weight 31, which may be fixed in various positions on the extension and fastened thereon by set screws 32. Pivoted to the end of the arm 95 30 is a depending pawl member 33. The member 33 has an elongated slot 34 near the center thereof, by means of which it is guided by a pin 35, and upon which pin it is adapted to slide. The lower end of member 33 is formed as a pawl tooth and is arranged to contact with a notch 36 formed near one end of an arm 37, which is pivoted to a bracket 38 rigidly secured to the bin 100 structure, or other fixed support. The arm 110

37 is normally disposed in substantially horizontal position, and a rod 39 passes therethrough near its outer end, said rod having on its end an enlarged portion 40 to prevent its withdrawal through the arm 37. This rod 39 carries a weight 41 and is connected at its other end to an alarm device 42. The weight 41 is adjustable on said rod.

The parts of the alarm normally occupy a relation shown in Fig. 2 with the bin board 20 projecting into the bin, substantially in the position shown in Fig. 1. The grain is conveyed into the bin through the opening 5 and accumulates therein in a heap, as shown at 43 in Fig. 1. When the grain reaches the position of the board 20 and mounts still higher, the board is successively raised to higher position, as indicated in dotted lines in Fig. 1. Owing to the disposition of pivot 18, the elevation of board 20 pulls on the flexible member 21 and the enlarged portion 25 at the end of the flexible member eventually lifts arm 29 of the bell crank member 24. This, in turn, lifts member 33; and the tooth at the end thereof, is disengaged from the pivoted arm 37. Owing to the weight 31, this arm then falls and allows the rod 39 to descend. This rod is arranged so that when it descends, it causes the alarm to sound, either by connecting an open electrical circuit, or by releasing a spring, or other alarm device. Upon hearing the alarm, the attendant will know that the bin has been filled to a sufficient amount, and will then switch the conveying machinery to discharge into an empty bin.

It will be understood that one alarm will suffice for any number of bins, each alarm device being arranged in operable relation thereto by any suitable connection. Attention is also called to the fact that the parts are shown somewhat diagrammatically, in Fig. 1, and reference will be had to Fig. 2, for the specific structure of the device.

It may also be stated that to stop the alarm, the attendant can simply pull down on member 21. This will sink the board 20 into the grain sufficiently to give room to depress member 29 and again set pawl 36 by raising rod 39. The device is then set for the next filling of the bin, as the discharge of the grain will not affect the same.

Generally stated, the invention consists in the matter described, shown in the accom-

panying drawings and set forth in the 55 claims.

What I claim is:

1. In an alarm device for elevator grain bins, an alarm actuating means therefor, a trip device for controlling said means consisting of a pivoted arm, a pawl, and a bell crank lever, an adjustable weight on said bell crank lever and a flexible member for operating the bell crank lever to actuate the trip device and permit the alarm actuating member to sound the alarm.

2. In an alarm device for elevator grain bins, the combination of an alarm, an actuating rod for said alarm, an adjustable weight thereon, a pivoted arm through which said rod passes having therein a ratchet notch, a pawl engaging said notch and a bell crank lever adapted to be raised to withdraw the pawl from the notch and allow the alarm to be actuated.

3. In an alarm for elevator grain bins, a pivoted bin board adapted to be raised by accumulating grain, a flexible member attached thereto, a sheave adjacent the top of said bin over which said flexible member passes, an alarm device adjacent the bottom of the bin, a trip device comprising a weighted bell crank lever, and an alarm actuating member connected to the alarm device for operating the same, and actuated by the bell crank lever, said flexible member extending down to and being connected to said trip device whereby when said board is raised the alarm will be operated.

4. An alarm device for elevator grain bins having in combination a pivoted bin board adapted to be raised by accumulating grain, a flexible member connected thereto, a weighted bell crank lever disposed adjacent the bottom of the bin, a lever connected thereto and adapted to detachably engage an alarm operating member, said cable being attached to said bell crank lever, whereby when the bin board is raised, the bell crank lever will be turned to cause the lever connected thereto to release the alarm actuating member.

In testimony whereof I affix my signature in presence of two witnesses.

ALBERT O. MILLER.
